(57) **CLAIM**

The ornamental design for a roof for a toilet cubicle, as shown and described.

DESCRIPTION

FIG. 1 a left-side frontal perspective view of a roof for a toilet cubicle according to my new design;

FIG. 2 a side perspective view of the roof for a toilet cubicle shown in FIG. 1; and,

FIG. 3 a plan view of the roof for a toilet cubicle shown in FIG. 1.

The broken lines depict environment and form no part of the claimed design.

1 Claim, 3 Drawing Sheets
